(57) **CLAIM**

The ornamental design for a grille surround for a vehicle, as shown and described.

DESCRIPTION

This application contains subject matter related to the following co-pending U.S. design patent applications: application Ser. No. 29/763,257, filed Dec. 22, 2020 and entitled “TRUCK CAB, TOY, AND/OR REPLICAS THEREOF;” and application Ser. No. 29/763,258, filed Dec. 22, 2020 and entitled “TRUCK CAB, TOY, AND/OR REPLICAS THEREOF.”

FIG. 1 is a right, front perspective view of a grille surround for a vehicle according to the design;

FIG. 2 is a front view thereof;

FIG. 3 is a left side view thereof;

FIG. 4 is a right side view thereof; and,

FIG. 5 is a top view thereof.

The broken lines in the drawings illustrate environmental subject matter only and form no part of the claimed design.

1 Claim, 5 Drawing Sheets
